UNITED STATES PATENT OFFICE.

WALTER L. SIEWERS, OF WINSTON-SALEM, NORTH CAROLINA, ASSIGNOR TO THE MALINE MILLS COMPANY, OF FORSYTH COUNTY, NORTH CAROLINA, A CORPORATION OF NORTH CAROLINA.

LADY'S UNDERGARMENT.

Application filed June 20, 1923. Serial No. 646,636.

To all whom it may concern:

Be it known that I, WALTER L. SIEWERS, a citizen of the United States, residing at Winston-Salem, in the county of Forsyth 5 and State of North Carolina, have invented certain new and useful Improvements in Ladies' Undergarments; and I do hereby declare the following to be a full, clear, and exact description of the invention, such as 10 will enable others skilled in the art to which it appertains to make and use the same.

This invention relates to lady's undergarment, and has for its object to provide a garment which can be made without waste 15 of material as regards the main body of the garment. The main body of the garment is formed from a tabular member of substantially the same diameter throughout and the same is slit from its bottom to a point 20 intermediate its ends and a gusset is inserted to give the necessary width at the bottom of the garment.

The various novel features of the invention will appear from the detailed description 25 of the invention taken in connection with the accompanying drawings forming a part of this specification.

In the drawings Fig. 1 is an elevation of the tabular member from which the 30 proved garment is formed. Fig. 2 is an elevation of the finished garment, Fig. 3 is a plan view of one of the pieces which is inserted into the garment to provide the necessary width at the bottom thereof; Fig. 35 4 is a view similar to Fig. 2, but showing the gusset having a rounded apex instead of a pointed apex, and Fig. 5 is a cross section taken on line 5—5 of Fig. 2.

In the drawings numeral 1 indicates the 40 conventional shoulder straps at the top of the body 2, which comprises the main portion of the garment, and 3 the usual drawstring at the top of the garment.

The body 2 is a knitted tabular member 45 of substantially uniform diameter throughout and the same is slit at the front and back as at 4 from the bottom upwardly.

Inserted into the slits 4 at the front and back are gussets 5, these gussets being connected by a tab 6. The gussets at their apex are perfectly pointed as shown in Fig. 2 but it is within the spirit of the invention 50 to make them rounded as in Fig. 4.

While it is preferred to make the tab 6

an integral part of the gussets 5, nevertheless, it is within the spirit of the invention to make the tab as a separate member and to sew it to the gussets 5.

The tab 6 connects the bases of the gussets, and hence the two gussets can be conceived 60 of as being double arrowhead gussets. The tab 6 is relatively narrow and of sufficient length to permit one side or the other or the lower part of the garment to be drawn up over the hip without binding in the crotch. 65 The insertion of the gussets causes the sides of the garment on either side of the connecting portion of tab 6 to extend upwardly away from the said connection portion. It 70 will thus be seen that the elongated tab or connecting portion together with the upwardly extending side of the garment permits the garment to be readily drawn up as stated.

A garment made in accordance with this 75 invention can be readily manufactured at a minimum cost, since it is merely necessary to slit the tube 2 and insert the double arrow-head gussets into the slits to provide the necessary and desired width at the bottom of the garment.

What I claim is:

1. A garment comprising a tabular body slit longitudinally in front and back from the bottom edge upwardly, and connected arrowhead gussets inserted into the body at the said slit, the connection between the arrowheads, tying the front and back of the garment together, being relatively long and narrow, and the bottom of the garment at 80 either side of the said connection extending upwardly away from said connection.

2. A garment comprising a tabular body slit longitudinally in front and back from the bottom edge upwardly, and a double 85 arrowhead gusset piece inserted into the slit part of the body, the connection between the arrowheads of the gussets being of less width than the widest part of said arrowheads and being relatively long and tying 90 the front and back of the garment together, the bottom of the garment at either side of said connection extending upwardly away from said connection.

In testimony whereof I affix my signature.

WALTER L. SIEWERS.
